TRANSCRIBING MACHINE

Edgard R. Wiklund, Dunwoody, Robert N. Fink, Decatur, and John Jamgochian, Jr., and Larry W. Lee, Atlanta, Ga.; said Lee assignor to said Wiklund, said Fink and said Jamgochian, fractional part interest to each

Filed July 17, 1972, Ser. No. 272,161

Term of patent 14 years

Int. Cl. D14—01

U.S. Cl. D26—14 B

FIG. 1

FIG. 2

FIG. 3

FIG. 4

FIG. 5

FIG. 1 is a top plan view of a transcribing machine embodying our new design;

FIG. 2 is a front elevational view thereof;

FIG. 3 is a rear elevational view thereof;

FIG. 4 is a side view of the left hand side thereof; and

FIG. 5 is a side view of the right hand side thereof.

We claim:

The ornamental design for a transcribing machine, substantially as shown.
